[57] CLAIM

The ornamental design for a facial cleaning apparatus, substantially as shown and described.

DESCRIPTION

FIG. 1 is a perspective view of a facial cleaning apparatus showing my new design;

FIG. 2 is a perspective view of a second embodiment thereof, wherein the only difference resides in the number of bristled heads;

FIG. 3 is a top plan view of the embodiment shown in FIG. 1;

FIG. 4 is a bottom plan view thereof;

FIG. 5 is a left side elevational view thereof;

FIG. 6 is a rear elevational view thereof;

FIG. 7 is a right side elevational view thereof;

FIG. 8 is a front elevational view thereof.
